TROLLEY WIRE CONTACT DEVICE

John L. McGlothlen, Pittsburgh, Pa., assignor to
 The Martin Hardsoog Co., Pittsburgh, Pa., a
 corporation of Pennsylvania

Application May 31, 1952, Serial No. 290,894.

16 Claims. (Cl. 200—51.07)

1

This invention relates to an electrical connector, and more particularly, to an improved connector for making a detachable electrical connection to a source of electrical potential such as a trolley wire or the like.

In single wire systems, such as trolley wires, the electrical energy is transmitted over a bare conductor which is operative to supply electrical energy to apparatus having one terminal connected to the wire and the other to the ground. It frequently is desirable to make a connection to the trolley wire for operating auxiliary apparatus adjacent the trackway over which the trolley wire is located. The conventional manner of making such connections is to provide a terminal connector having a hook or clamp which is placed in direct engagement with the trolley wire to make the connection. One disadvantage of conventional connectors is that they must be removed to permit a trolley to pass by without becoming disconnected from the trolley wire. Another and more serious disadvantage of conventional connectors is that they introduce a considerable element of danger to the workmen making a connection. This danger is due to the possibility of leakage conducting paths being created through which the trolley wire may be connected through the workman to ground thereby resulting in injury and sometimes death to the workman. Such leakage paths are most commonly due to the accumulation of dirt on the insulation of the connector held by the workman when making the connections. As is well known, a dirty handle becomes a fairly good conductor of electricity, particularly when the dirt is saturated with oil or wet with water. This danger is quite common where the trolley wire is located underground in mines, in which case considerable dirt and water is encountered.

One of the principal objects of this invention is to provide a connector for making a connection to a trolley wire which is operable to eliminate the danger of grounding the trolley wire through the workman making the connection. To this end, there is provided a connector having an insulating handle and a contact which is movable by manipulation of the handle to make a connection with a stationary contact in electrical conducting engagement with the trolley wire. The handle is provided with a conducting element projecting outwardly therefrom for engagement with a grounding element. The conducting element is so arranged that it will engage with the grounding element to place the handle at ground potential prior to the establishment of a

2

connection through the contact carried by the handle. In this manner, there is established a direct connection of the handle to ground, thereby preventing grounding of the trolley wire through the workman and thus preventing injury to the workman.

Another object of this invention is to provide a connector for making an electrical connection of auxiliary apparatus to a trolley wire which will not interfere with the movement of the trolley along the wire and by the connection.

This application is a continuation-in-part of my application Serial No. 38,489, filed July 13, 1943, for "Trolley Wire Contact Device," now abandoned. One of the main uses of the trolley wire connector of the type shown in application Serial No. 38,489 is in underground mining, particularly coal mining. Practically all coal mining operations are carried on with electrical equipment, and the electrical current is distributed through the mine by trolley wires. Some machines and tools, such as power coal cutting machines, drills and loading machines, are portable and are moved about in the mine entries and rooms as they are extended. Since these machines perform heavy service, high electrical amperage current is required so that good contacts and safe connections are required. Further underground mining creates much dust and dirt and often water is present in the workings, so that it is important to have connections with the trolley wire that will not be short-circuited to the ground by the accumulation of dust and moisture.

Accordingly, a further object of the invention is to provide a trolley wire support on which a connector may be mounted to make a good electrical connection with the trolley wire.

A still further object of the invention is to provide a connector by which a good electrical connection may be made with a trolley, and the connection mechanism shielded to prevent short-circuiting and a connection with ground of a person handling the connector.

Other objects and advantages of the invention will become apparent from the following description.

In the drawings, there is shown a preferred embodiment of the invention. In this showing:

Fig. 1 is a side elevational view of a connector constructed in accordance with the principles of this invention, a part of the apparatus to which it is connected being broken away and shown in

Fig. 2 is an end view of the structure shown in Fig. 1;

Fig. 3 is a longitudinal sectional view of the connector shown in Figs. 1 and 2;

Fig. 4 is a bottom plan view of a modified form of trolley wire support in which a trolley connector may be mounted to make an electrical connection at each side of the trolley wire;

Fig. 5 is a vertical sectional view taken on the line V—V of Fig. 6 of an improved trolley wire support showing in section a trolley connector mounted therein;

Fig. 6 is a sectional view of the trolley wire support taken on the line VI—VI of Fig. 5;

Fig. 7 is a view in side elevation of the preferred form of trolley connector;

Fig. 8 is a bottom plan view of a portion of the trolley connector shown in Fig. 7; and

Fig. 9 is a vertical sectional view of the trolley connector taken on the line IX—IX of Fig. 8.

Referring to Figs. 1 and 2 of the drawings, the numeral 1 designates a trolley wire which is carried by clamping members 2 having a nut 3 and bolt 4 for holding them in clamping engagement with the wire 1 as indicated. The clamping members 2 are secured to and supported by insulation 5 bonded to a supporting housing 6 which is formed of metal. A threaded mounting member 7 is connected to the upper part of the housing 6 to provide a connection by which the entire structure may be secured to a support. As illustrated, the mounting member 7 is secured to a wood plug 8 which is adapted to be driven into an opening formed in the roof of a mine. When the roof of a mine is not solid, a hole is drilled therein for the reception of the plug 8 into which the fastening member 7 is threaded, the fastening member 7 being provided with threads (not shown) at its upper end. Where the roof of a mine is solid, it is not necessary to employ the wood plug 8 and a metal support for threaded engagement with the member 7 may be employed in accordance with conventional practice. The parts thus far described comprise a conventional support for an underground trolley wire and form no part, per se, of this invention.

Since in ordinary usage, the plug 8 would operate to insulate the member 7 and housing 6 from ground, a copper wire or strip 9 is secured to the outer surface of the plug and has a part thereof in electrical engagement with the member 7 as at 9'. In this manner the strip 9 will be in tight engagement with the roof structure of the mine when the plug is mounted in position and will be effective to provide a ground connection for the housing 6 for a purpose to be described. Obviously, the copper strip 9 is not necessary where a metal anchor for the member 7 is provided in place of the plug 8.

The connector for making an auxiliary connection to the trolley wire 1 is indicated as a whole by the numeral 10 and is provided with an elongated body 11 formed of insulating material which provides a handle by which the connector may be manipulated when making a connection. As best shown in Fig. 3, the body member 11 is hollow and is provided with an opening 12 for the reception of an insulated conduit 13 by which the power may be fed from the trolley wire to the auxiliary apparatus. The inner terminal end of the conduit 13 is connected to a conductor strap 14 which is secured in position on an insulating support 15 which is preferably molded from suitable insulating material. A conductor strap 16 is mounted on the support 15 at a point spaced

from the strap 14 and is connected with a part 17 projecting outwardly through an opening in the insulation 15. The part 17 is bent at right angles to the strap 16 and provides a movable contact for a purpose to be described. The conductor straps 14 and 16 are provided with conducting clamps 18 for engagement with the ends of a fuse 19 which provides a protective connection between straps 14 and 16. The housing 11 is provided with a threaded connection to the body of the insulating support 15 and a screw 20 is provided for preventing rotation of the housing 11 on its support 15. An annular flange 21 is provided on the insulating support 15 at the inner end of the handle on housing 11 to prevent accidental contact with the movable contact 17.

A grounding element 22 in the shape of a rod formed of conducting material has its inner end secured in the insulating material of the support 15. The rod 22 extends outwardly from an opposite side of the flange 21 with respect to the handle 11 and is operable to place the handle 11 at ground potential in a manner to be described.

A grounding element comprising a cylinder 23 formed of metal is clamped in position on the housing 6. The cylinder 23 is in contacting engagement with the surface of the housing 6 and is thus connected to ground through the housing 6 and mounting member 7.

The clamping members 2 have a conductor strap 24 secured thereto as by welding. The conductor strap is provided with a pair of contact elements 25 at its outer end to provide a notch for the reception of the movable contact 17.

The above described arrangement of the grounding element or cylinder 23 and strap 24 illustrates the present preferred embodiment of the invention. By this arrangement, trolley wire insulating supports already in position may be readily adapted for use with the connector 10. To do so, it is merely necessary to clamp the cylinder 23 in position on the grounded supporting member 6 and to weld the conducting strap 24 to one of the trolley wire clamps 2 or bolt 4. However, it will be apparent that the invention may be adapted to trolley wire supports before they are mounted in position on the roof of a mine. In such case, the cylinder 23 would be cast integrally with the housing 6 or secured thereto in some other fashion during the fabrication of the insulating support. In like manner, the conducting strap 24 or stationary contact members 25 would be formed integrally with one of the trolley clamping supports 2.

In order to connect the conduit 13 to the trolley wire 1, the handle 11 is manipulated to insert the grounding element 22 into the opening provided in the cylindrical element 23. The engagement of the ground element 22 with the cylindrical element 23 provides a connection for the insulating material of the handle 11 with ground. With the rod 22 positioned in the cylindrical element 23, the handle 11 is then rotated to move the movable contact 17 from the position shown in Fig. 2 to a position between the contacts 25. There will then be provided direct electrical connection between the trolley wire 1 and the cable 13. It will be seen that the cylinder 23 provides a support for the handle 10 during its manipulation to make an electrical connection with the contacts 25.

By reason of the grounding connection provided by the rod 22, it will be seen that injury to the workman holding the handle 11 is effectively prevented. In the event that the conducting

condition of the outer surfaces of the handle 11 is such that electric current would flow thereover, such current will be conducted to the ground rod 22 thereby preventing injury to the workman holding the handle 11. By securing the stationary contact to the clamping elements 2 it will be seen that the connection is out of the way of a trolley moving over the trolley wire 1 and it will thus not be necessary to interrupt the connection so that a trolley may pass by as is the case with conventional connectors.

The preferred form of the trolley wire connector illustrated in Figs. 4 to 9 inclusive differs from the connector of Figs. 1 and 3 in the mounting of the contacts which are made 15 between the trolley wire and the connector handle. The construction of Figs. 4 to 9 inclusive complies with the mine safety regulations.

Referring to Figs. 5 and 6, the trolley connector bracket 26 has a boss 28 on the back thereof adapted to receive a threaded fastening member such as 7 which is secured in the roof of a mine. An insulator 30 is secured within the bracket 26 for the purpose of insulating and supporting a trolley wire 1. The trolley wire is connected to a square or rectangular shank 32 which is embedded within the insulator and arranged to position wire clamps 2 having a contact blade 34 thereon parallel to the trolley wire. This 30 arrangement insures that when the bracket is properly positioned for supporting the trolley wire, the contact blade will be parallel to the trolley wire. A tubular grounding member 36 is connected to a separable bracket 38 (Fig. 6) which in turn is connected to the bracket 26 by means of pins 40 and bolt 42. The bracket 38 is made in two parts, and bolt 42 extends through one part and is threaded into the other. The pins 40 extend into openings 44 in the bracket in order to position the tubular member 36 at right angles to the trolley wire. Within the tubular member 36 is mounted a bronze ferrule 46 which is split and bent inwardly in order to make a tight yielding contact with a pin 48 (Figs. 5 and 6) on a connector handle when the pin is inserted in the ferrule. It is important to maintain a tight, accurate contact between the pin and the ferrule in order to properly close the contact members which connect the handles with the trolley wire.

In Fig. 4 is shown a bracket having two tubular members 50 and 52 which are formed integral with the bracket 26. In this form of bracket, contact blades 54 are connected with each of the trolley wire clamps so that a connector handle may be mounted on either side of the trolley wire.

The preferred form of the connector handle is illustrated particularly in Figs. 7, 8 and 9. This handle consists of a hollow insulation body 56, such as Micarta, which is connected to an insulation head 58 by means of a threaded connection 60. A forked switch contact member 62 is mounted in the insulation head 58 within a cavity 64. The cavity is open at one side and the bottom, so that when the contact member 62 is moved into contact with the contact member 34 on the trolley bracket, a portion of insulation 66 of the head will cover the switch contacts so that dirt will not settle above the switch contacts (see Fig. 5) that might result in a short circuit of the electrical circuit. The switch member 62 is connected by means of a bar 68 with a metal cylindrical connector 70 which receives one end of a fuse 72. The other end of the fuse is mounted in a cylindrical connector 74, which in turn is

connected with an insulated cable 76, the cable being held in position by means of a screw 78. The cable extends through the rear end of the handle, but a considerable portion of the cable is mounted within the insulated handle. At the rear of the connector 74 is mounted a rubber gasket 80, and a rubber gasket 82 is mounted in the front end of the handle adjacent the threaded connector 60. Therefore when the handle is closed the gaskets are compressed to make the interior of the handle moistureproof. The connecting pin 48 for the ground connection is mounted in the head 58 of the handle and is arranged to move through the ferrule 46 on the bracket when the handle is connected with the trolley line bracket.

With the arrangement described above, the contact blades for the trolley line will be arranged parallel to the trolley line, and the tubular members for positioning the contact handle arranged to position the contact member in the handle, so that when the handle is rotated in the tubular member, the fork switch member 62 will clamp down over the knife blade 34 to make a good electrical connection. From Fig. 5 also it will be seen that the switch contacts are covered when the switch contacts are closed. Preferably the top of the knife-like blade is sharpened to prevent dust and dirt in the atmosphere from building up on the blade to make a grounding contact and thus short circuit the electrical circuit of the trolley wire.

The preferred form of the invention having been thus described, what is claimed as new is:

35. 1. An electrical connector for making a detachable connection to a trolley wire or the like comprising a handle formed of insulating material, a stationary contact connected with said wire, a movable contact mounted on said handle for movement thereby into engagement with said stationary contact, a member at ground potential and having a cylindrical opening therein, and a rod projecting outwardly from said handle, said rod being receivable in said opening to place said handle at ground potential, said member forming a pivot support for said handle about which said handle may be rotated to move said movable contact into engagement with said stationary contact.
40. 2. In an electrical connector for making a detachable connection to a trolley wire or the like having supporting structure including a conducting member at ground potential, a conducting member in contact with said trolley wire, and electrical insulation between said members, the combination comprising a handle formed of insulating material, a grounding element having an opening therein connected to said ground conducting member, a rod embedded in the insulation of said handle and receivable in said opening to place said handle at ground potential, and a contact carried by said handle, said grounding element providing a pivot support about which said handle may be rotated to engage said contact with said conducting member in contact with said trolley wire.
45. 3. In apparatus for making a detachable electrical connection to a conductor having a support, the combination comprising a mounting part having a circular opening therein secured to said support, a stationary contact part on the support and electrically connected with the conductor, a handle formed of a body of insulating material and having a mounting rod projecting therefrom, said rod being receivable in said open-
50. 4. In an electrical connector for making a detachable connection to a trolley wire or the like having supporting structure including a conducting member at ground potential, a conducting member in contact with said trolley wire, and electrical insulation between said members, the combination comprising a handle formed of insulating material, a grounding element having an opening therein connected to said ground conducting member, a rod embedded in the insulation of said handle and receivable in said opening to place said handle at ground potential, and a contact carried by said handle, said grounding element providing a pivot support about which said handle may be rotated to engage said contact with said conducting member in contact with said trolley wire.
55. 5. In an electrical connector for making a detachable connection to a trolley wire or the like having supporting structure including a conducting member at ground potential, a conducting member in contact with said trolley wire, and electrical insulation between said members, the combination comprising a handle formed of insulating material, a grounding element having an opening therein connected to said ground conducting member, a rod embedded in the insulation of said handle and receivable in said opening to place said handle at ground potential, and a contact carried by said handle, said grounding element providing a pivot support about which said handle may be rotated to engage said contact with said conducting member in contact with said trolley wire.
60. 6. In an electrical connector for making a detachable connection to a trolley wire or the like having supporting structure including a conducting member at ground potential, a conducting member in contact with said trolley wire, and electrical insulation between said members, the combination comprising a handle formed of insulating material, a grounding element having an opening therein connected to said ground conducting member, a rod embedded in the insulation of said handle and receivable in said opening to place said handle at ground potential, and a contact carried by said handle, said grounding element providing a pivot support about which said handle may be rotated to engage said contact with said conducting member in contact with said trolley wire.
65. 7. In an apparatus for making a detachable electrical connection to a conductor having a support, the combination comprising a mounting part having a circular opening therein secured to said support, a stationary contact part on the support and electrically connected with the conductor, a handle formed of a body of insulating material and having a mounting rod projecting therefrom, said rod being receivable in said open-
70. 8. In an electrical connector for making a detachable connection to a trolley wire or the like having supporting structure including a conducting member at ground potential, a conducting member in contact with said trolley wire, and electrical insulation between said members, the combination comprising a handle formed of insulating material, a grounding element having an opening therein connected to said ground conducting member, a rod embedded in the insulation of said handle and receivable in said opening to place said handle at ground potential, and a contact carried by said handle, said grounding element providing a pivot support about which said handle may be rotated to engage said contact with said conducting member in contact with said trolley wire.
75. 9. In an apparatus for making a detachable electrical connection to a conductor having a support, the combination comprising a mounting part having a circular opening therein secured to said support, a stationary contact part on the support and electrically connected with the conductor, a handle formed of a body of insulating material and having a mounting rod projecting therefrom, said rod being receivable in said open-

ing to mount said handle on said support for rotational movement in opposite directions relative thereto, and a contact element mounted on said handle for engagement with said stationary contact part to complete an electrical connection, manual rotation of said handle in opposite directions with said rod in said opening being effective to move said contact element into and out of engagement with said stationary contact part to make and break said electrical connection.

4. In apparatus for making a detachable electrical connection to a trolley wire, the combination comprising an insulator support for the trolley wire including a mounting part at ground potential, a grounding element having a circular opening therein and an electrical connection with said mounting part, and a stationary contact structure having an electrical connection with the trolley wire, said stationary contact structure comprising a pair of spaced parallel contact elements respectively in planes perpendicular to the axis of said opening, a handle formed of insulating material and having a mounting rod projecting therefrom, said rod being receivable in said opening to mount said handle on said support for rotational movement in opposite directions relative thereto, and a movable contact structure mounted on said handle comprising a knife-like contact element in a plane perpendicular to the axis of said rod, manual rotation of said handle in opposite directions with said rod in said opening being effective to move said knife-like contact element to and from a position between said spaced parallel contact elements in which it completes an electrical connection between said stationary and movable contact structures.

5. In apparatus for making a detachable electrical connection to a trolley wire, the combination comprising an insulator support for the trolley wire including a mounting member at ground potential, a first grounding element having an electrical connection with said mounting part, and a stationary contact structure having an electrical connection with the trolley wire, a handle formed of insulating material and having a second grounding element projecting therefrom for engagement with said first grounding element to place said handle at ground potential, and a movable contact structure mounted on said handle for movement thereby into engagement with said stationary contact structure, and means including said first and second grounding elements forming a rotatable mount for said handle on said insulator support about which it may be rotated to move said stationary and movable contact structures into and out of engagement with each other.

6. In apparatus for making a detachable electrical connection to a trolley wire, the combination comprising an insulator support for the trolley wire including a mounting member at ground potential, a grounding element having an electrical connection with said mounting part, a stationary contact structure having an electrical connection with the trolley wire, a movable contact structure on the insulator support having an electrical conductor connected therewith, and means including said grounding element forming a rotatable mount for the movable contact structure about which the movable contact structure may be rotated into and out of engagement with said stationary contact structure.

7. A separable connector of the class described comprising a support member and a connector

member, said members having interfitting metal pin and sleeve elements for slidably interengaging each other and forming a separable union between the two members, the support member including a metal trolley wire bracket connected with a trolley wire, a grinding insulator for the bracket, and an anchor part carrying the insulator, one of said interfitting elements first mentioned being on the anchor part of the supporting member, the connector member comprising an insulating body on which the other of said interfitting elements is mounted, a contact on the insulating body of the connector member, a contact on the supporting member electrically connected with the trolley, the said contacts of the respective members being offset with respect to the interfitting elements of the respective members to require the engagement of the interfitting elements before the contacts can be engaged and remain interfitted until after the contacts have been disengaged, the relative sliding movement of said elements serving to guide the contacts into and out of engagement, and means for connecting a cable with the contact of the connector member.

8. The trolley wire connector defined in claim 7 in which the sleeve element of the connector member is substantially at right angles with the trolley wire and the contacts on the supporting and connector members are arranged to make sliding contacts with each other in a plane at right angles to the axis of the sleeve axis.

9. An electrical connecting device for a power takeoff from a trolley line comprising a grounded trolley wire supporting bracket, an insulator carried by said bracket to which the wire is connected, a thin blade contact connected with the line and insulator, said blade being supported in a vertical position, a tubular grounded contact member mounted on the bracket, a separable connector comprising an insulating handle having a grounding pin arranged to slidably enter the tubular member on the bracket, a contact in the handle arranged to make electrical contact with the trolley contact when the handle is rotated about the tubular member, said tubular contact member and the grounding pin being arranged so that the pin extends a substantial distance into the tubular member before the contact for the trolley wire and the handle connector may be brought into contact with one another, and a cable connected with the contact in the handle.

10. The connecting device defined in claim 9 in which the contact in the handle consists of a pair of spaced contact jaws so positioned in the handle that the handle will cover the contacts when the contacts are closed.

11. The connecting device defined in claim 9 in which the contact blade connected with the trolley line is positioned parallel with the trolley line and the grounding tube is mounted at right angles to the trolley line to position the handle away from the trolley line.

12. The connecting device defined in claim 9 in which a rectangular supporting shank is embedded in the trolley insulator and connected with the trolley line to position the trolley line contact blade parallel to the line.

13. The connecting device defined in claim 9 in which the tubular ground contact is removably attached to the bracket and arranged to hold the tubular member at right angles to the trolley line.

14. The connecting device defined in claim 9

in which tubular grounding contact members are mounted one extending out at each side of the bracket to permit electrical connection at either side of the trolley.

15. The connecting device defined in claim 9 in which a yieldable clamping ferrule is positioned within the tubular member to align the handle in position for making contact connections.

16. The connecting device defined in claim 9 in which the handle is a hollow body of insulation material having a fuse and cable connections therein having a threaded connection with a closed insulation head, an opening at the rear of the handle to receive an insulated cable and gaskets mounted within the handle at the front

and rear thereof to seal the interior of the handle against moisture entrance.
